UNITED STATES PATENT OFFICE

ELI J. MASON AND HERBERT L. CROFT, OF CALAMUS, IOWA; E. L. MILLER, ADMINISTRATOR OF SAID HERBERT L. CROFT, DECEASED, ASSIGNOR TO SAID MASON

HARROW DRAWBAR AND HINGE THEREFOR

Application filed January 27, 1930. Serial No. 423,843.

This invention relates to harrow drawbars of that type made up of hingedly connected sections, one of the objects of the invention being to provide hinges of novel construction for connecting the sections, these hinges having means whereby the pull exerted in drawing the harrow can be distributed to the pintles of the hinges so that the several sections of the drawbar will not sag rearwardly while the structure is in use.

Another object is to provide a drawbar structure that constitutes an improvement upon the device disclosed in Patent 1,430,825, issued to Mason and Lund.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a plan view of a draw-bar having the present improvement combined therewith.

Figure 2 is an enlarged plan view of one of the hinges.

Figure 3 is a horizontal section through portions of one of the hinges.

Referring to the figures by characters of reference, 1 designates the middle section and 2 designates the end sections of a drawbar. It is essential that these sections be connected by means of hinges so that they can be folded to allow the drawbar and the sectional harrow connected thereto to pass through a relatively narrow space, such as a gate opening. While hinges have been provided for this purpose, it has been found that they have been subjected to excessive strain while the device is in use so that they have not stood up under working conditions for any considerable length of time.

In the present instance each hinge is designed primarily to withstand the rough

usage to which the drawbar is subjected. As shown particularly in Figures 2 and 3, each hinge is formed of plates or leaves 3 and 4 respectively which can be cut away at their centers as shown at 5 to reduce their weight 55 and cost of production. Each leaf 3 is provided at one end with spaced sleeves 6 located at the front and back edges of the leaf, each leaf being reinforced by a web 7 as shown. Interposed between and bearing against the 60 inner ends of the sleeves 6 are additional sleeves 8 formed at one end of the leaf 4, these sleeves 8 being also reinforced by integral webs 9.

Seated within the sleeves 6 and 8 is a tubular pintle 10 which holds the sleeves in proper alignment and provides a bearing therefor. The pintle has its ends flush with the exposed ends of the sleeves 6 and extending through said pintle is a draft bolt 11. An eye 12 is 70 located at the front end of the bolt while the back end thereof is screw-threaded and engaged by a nut 13 located thereto by any suitable means such as a cotter pin 14. The eye 12 and the bolt 13 cooperate to hold the pintle 75 10 against longitudinal displacement relative to the sleeves 6 and 8.

In practice the leaves 4 are attached to the end portions of the drawbar section 1 while the leaves 3 are attached to the sections 2. 80 Thus section 2 can be pulled inwardly onto the section 1. Links 15 are secured in the eyes 12 and converge to a ring 16 which, in turn, can be connected by links 17 to the middle portion of the section 1. These parts 85 are all so proportioned that when a pull is exerted on the ring 16 power will be transmitted through all of the links to the center of the bar 1 and to the eyes 12. Thus the drawbar will be pulled forwardly not only 90 at the center of the section 1 but also at the centers of the hinges and it becomes possible for the drawbar to withstand all severe strain to which it is subjected while in use without danger of distorting or breaking the hinges. 95

While the drawbar has been shown of three hingedly connected sections it is to be understood that it can be made of more than three sections. In every case, however, the sections are connected by hinges such as described and 100

all of the hinges are connected in turn to the ring 16.

What is claimed is:

The combination with relatively movable sections of a harrow drawbar, of a hinge connection between the sections including leaves attached to the respective sections, alining sleeves thereon, a tubular pintle extending through all of the sleeves for transmitting transverse thrust from one section to the other, a draw bolt extending through the pintle and relieved thereby from transverse thrust, and a draft element attached to the front end of the bolt, said bolt constituting means for transmitting longitudinal pull from the draft element to the back ends of the hinges at the sleeves.

In testimony that we claim the foregoing as our own, we have hereto affixed our signatures.

**ELI J. MASON.
HERBERT L. CROFT.**
